UNITED STATES PATENT OFFICE.

ALEXANDER M. ALEXANDER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TRANSMISSION DEVICE.

1,294,594.

Specification of Letters Patent. Patented Feb. 18, 1919.

Application filed May 16, 1917. Serial No. 169,092.

To all whom it may concern:

Be it known that I, ALEXANDER M. ALEXANDER, a citizen of the United States, residing at Beverly, in the county of Essex and 5 State of Massachusetts, have invented certain Improvements in Transmission Devices, of which the following description, in connection with the accompanying drawings, is a specification, like reference characters 10 on the drawings indicating like parts in the several figures.

This invention relates to machines for operating upon stock and more particularly to that class of such machines in which the 15 stock is operated upon by a plurality of separate and successively acting instrumentalities while passing through the machine, the illustrative machine being an improvement upon that of United States Patent No. 20 1,078,664.

The machine chosen for illustrative purposes is a leather skiving machine since the invention finds a practicable application in such a machine. It is desirable in leather 25 skiving machines to start the rotation of the knife before starting the actuation of the feed mechanism so that the knife shall be revolving rapidly when the stock is fed to it. It is also desirable, particularly when 30 skiving spongy stock or pieces having irregular outlines to be able to vary the rate of feed of the leather without varying the rate of rotation of the knife.

According to one feature of the invention 35 the shaft which drives one of the instrumentalities for acting upon the stock, for example the feed roll, has mounted upon it both a pulley for driving another instrumentality, for example the skiving knife, 40 and a power pulley; and means are provided for successively clutching the power pulley to the driving pulley and the driving pulley to the shaft.

This and other features of the invention 45 including certain details of construction and combinations of parts will be described in connection with an illustrative machine and pointed out in the appended claims.

Referring to the accompanying drawings, 50 Figure 1 is a front elevation of a leather skiving machine in which the present invention is embodied, and

Fig. 2 is a vertical longitudinal section through the transmission mechanism.

55 Referring first to Fig. 1, there is shown a

skiving machine having the usual feed roll 3, feed disk 5 and disk knife 7. The feed roll and feed disk are driven by gears and shafts as shown from a drive shaft 9, and the knife is driven by a belt 11 from a pulley 13. 60 The machine, except for the transmission mechanism, will not be described in detail since its construction *per se* forms no part of the present invention and is sufficiently described in Patent No. 1,078,664 which has 65 been referred to above. It will be understood that the leather or other stock is fed by the combined action of the feed disk 5 and feed roll 3 to the rotary skiving knife 7 with the result that the margin of the 70 stock is beveled. It will thus be clear that the machine is provided with a plurality of instrumentalities for acting upon the stock; first the disk 5 and roll 3 act to feed the stock, and second the knife 7 acts to 75 skive the stock.

Referring now more particularly to Fig. 2, the pulley 13 which drives the knife is loose on the shaft 9 and is provided with two clutch faces, an internal clutch face 15 80 and an external clutch face 17. Fast to the shaft 9 is a clutch member 19 having a clutch face 21 which is the complement of the clutch face 15, a ball thrust bearing 23 being located between said member and the 85 frame 29 of the machine. A stepped pulley 27 having a hardened steel or wooden button 30 tightly driven into its end is also loosely mounted on the shaft 9, said pulley being adapted to receive power from any 90 suitable source through a belt 31. This pulley 27 will be called a power pulley or member to distinguish it from the knife driving pulley 13. Between the knife driving pulley 13 and the clutch member 19 is a 95 comparatively heavy coiled spring 33; and between the power pulley 27 and the knife driving pulley 13 is a weaker coiled spring 35. A pin 36 driven through the shaft 9 limits the movement of the pulley 13 to the 100 right. A wedge-shaped block 37, vertically slidably in stationary guides and arranged to be moved by a treadle rod 39, contacts with the button 29. Depression of the treadle, not shown, by which the rod 39 is 105 pulled down thus moves the power pulley 27 to the left against the force of the spring 35 until the clutch face 17 of the pulley 13 engages the clutch face 41 of the power pulley whereupon the rotation of the knife 110

7 is started. Further downward movement of the wedge block 37 moves both the power pulley 27 and the knife driving pulley 13 to the left against the force of the spring 33 until the clutch faces 15 and 21 are engaged, whereupon the rotation of the shaft 9 and consequently the rotation of the feed mechanism is started. It is thus possible by pulling down on the rod 39 to start the knife 10 and then the feed mechanism. It is also possible, by varying the pressure of the clutch face 15 upon the clutch face 21 to vary the rate of feed of the work without varying the rate of rotation of the knife, 15 since the spring 33 is sufficiently stronger than the spring 35 to prevent separation of the clutch faces 17 and 41 until after the clutch faces 15 and 21 have separated.

Having thus described my invention, what 20 I claim as new and desire to secure by Letters Patent of the United States is:

1. A skiving machine, having, in combination, feed mechanism, a skiving knife, a shaft from which the feed mechanism is driven, a pulley from which the knife is driven, said driving pulley being loose on the shaft, a power pulley also loose on the shaft, and means for successively connecting the power pulley with the driving pulley 25 and the driving pulley with the shaft.
2. The combination with a plurality of instrumentalities for acting upon stock, of a shaft for driving one of said instrumentalities, a pulley loose on the shaft for driving another of the instrumentalities, a power pulley also loose on the shaft, and means for successively clutching the power pulley to the driving pulley and the driving pulley to the shaft.
3. The combination with a plurality of instrumentalities for acting upon stock, of a shaft for driving one of said instrumentalities, a pulley loose on the shaft for driving another of the instrumentalities, a power pulley also loose on the shaft, and means for moving first the power pulley into engagement with the driving pulley and then the driving pulley into engagement with the shaft.

Copies of this patent may be obtained for five cents each, by addressing the "Commissioner of Patents, Washington, D. C."

4. A transmission device having, in combination, a shaft, a clutch member fast thereto, a power pulley loose on said shaft, a driving pulley also loose on said shaft and located between said clutch member and said power pulley, and means for moving said power pulley toward said clutch member first to cause said power pulley to engage said driving pulley and then to cause said driving pulley to engage said clutch member.

5. A transmission device, having, in combination, a shaft, a power pulley and a driving pulley loose on said shaft, there being co-operating clutch faces on said pulleys, a clutch member fast to the shaft, there being 65 co-operating clutch faces on said member and driving pulley, a spring between said pulleys, a second spring between said clutch member and said driving pulley, and means for moving said pulleys to compress said 70 springs.

6. A transmission device, having, in combination, a shaft, a power pulley and a driving pulley loose on said shaft, there being co-operating clutch faces on said pulleys, a clutch member fast to the shaft, there being 75 co-operating clutch faces on said member and driving pulley, a spring between said pulleys, a stronger spring between said clutch member and said driving pulley, and means 80 for moving said pulleys to compress said springs.

7. A transmission device, having, in combination, a shaft, a clutch member fast thereto, a driving pulley loose on the shaft, 85 a stop carried by said shaft, a spring tending to hold the driving pulley away from the clutch member and against the stop, a power pulley also loose on the shaft, a spring acting to hold the driving pulley 90 and the power pulley in separated relation, and means for moving the power pulley into contact with the driving pulley and the driving pulley into contact with the clutch member.

In testimony whereof I have signed my name to this specification.

ALEXANDER M. ALEXANDER.
